DRUM-CARRIED TERMINAL WIPER

Robert W. Persons, Claremont, Calif.

Application May 19, 1953, Serial No. 356,004

3 Claims. (Cl. 200—166)

This invention has to do generally with terminal or contact wipers and is more particularly concerned with wipers particularly well adapted to the wiping of contacts of such mechanisms as tuners or channel selectors of television receiving sets, and to the novel combination of such selectors and wipers.

I will confine my description of the device to such a specific adaptation, but it is to be understood that this is not to be construed as limitative on my invention or on the broader claims appended hereto.

Channel selectors involve a bank of stationary contacts, and a rotatable drum having a series of contact strips whose contacts are selectively engaged with the stationary contacts by rotation of the drum. These contacts require relatively frequent cleaning, as is well understood in the art, in order to maintain good reception, and the cleaning operation is vexatious and time-consuming, as well as relatively costly. This is particularly true of the stationary contacts, for they are so relatively inaccessible as to require, for usual cleaning purposes, the removal of the tuner from the chassis, and then at least partial disassembly of the tuner.

In my copending application entitled Terminal Wiper, filed under instant date herewith, Serial No. 356,005, there is shown and claimed a wiper adapted to be applied to a housing flange, and to wipe and clean the drum contacts during normal channel-selecting rotation of the drum.

It is the major object of the present invention to provide a cleaning wiper carried by the drum and acting, during normal channel-selecting rotation of the drum, to wipe clean the stationary contacts, thus making separate cleaning operations unnecessary. Without conscious effort on the part of the set owner, the stationary terminals are constantly and automatically kept clean and bright—to obvious advantage.

It is also among the objects of my invention to provide a cleaning wiper which is of extremely simple construction and yet most efficient in operation. It is a special feature of the invention that the cleaner may be easily and quickly installed without the use of tools, and yet is securely held in place until such time as it is to be purposely removed—whereupon its detachment may be accomplished quickly and easily.

It is a further object of the invention to provide a novel association of such a cleaner and wiper with the drum of a channel selector.

Other objects and features of the invention will be apparent from the following detailed description, reference being made to the accompanying drawings, in which

Fig. 1 is a fragmentary plan view of a tuner or channel selector wherein my improved wiper is incorporated;

Fig. 2 is a section on line 2—2 of Fig. 1;

Fig. 3 is an enlarged fragmentary section taken from the position of line 3—3 in Fig. 1;

Fig. 4 is an enlarged fragmentary view of one of the drum flanges when the contact strip and cleaner are absent therefrom;

2

Fig. 5 is a perspective view of a usual contact strip for the drum;

Fig. 6 is a perspective view of the holder element of my improved wiper before the wiping pad has been applied thereto;

Fig. 7 is an enlarged end elevation of Fig. 6, as viewed from the position of arrow A;

Fig. 8 is an enlarged end elevation of Fig. 6, as viewed from the position of arrow B;

Fig. 9 is an enlarged section on line 9—9 of Fig. 1.

I have illustrated more or less conventionally some of the essential elements of one type of standard tuner or channel selector 10. Only a fragment of the tuner is shown, the showing being limited to such parts as are in some way concerned with the cleaning problem and my solution of that problem. Thus, the drum 11 has a shaft 12 which mounts the drum for rotation with respect to housing 13. A bank of stationary, spring terminals 14 is supported on a housing flange 15 and is positioned to be engaged selectively by drum contacts 16 when the drum is rotated, all the terminals of a given row 17 simultaneously engaging contacts 14 when the drum is rotated to a given position by manual operation of shaft 12.

The drum 11 is made up, in part, of a pair of axially spaced flanges 18 and 19 carried on shaft 12, the flange 18 serving as a support for elements to be described and being notched at 20 to receive spring pressed detent 20a whereby the contacts 16 are surely registered and releasably held in engagement with contacts 14 when the drum is rotated to select a given channel.

The peripheral face of the drum, proper, is made up of a plurality of non-conductive, transversely arcuate, contact strips 21a, each of these strips carrying a row 17 of contacts 16 which are selectively electrically connected to station selector coils 22 in a well known manner. The row 17 parallels and lies adjacent one edge of strip 21a. One end of the strip 21a is provided with spaced tongues 23a and the other end is provided with a wide central tongue 24a, the tongues 23a being taken within matching apertures 25 in drum flange 18, and tongue 24a being taken between lugs 26 on flange 19. Hooked spring tongues 27, integral with the flat spring ring 28 which is riveted to flange 19, spring over the tongues 24a to individually hold the strips releasably in position. It will be seen that by springing back a given tongue 27 a given strip 21a may easily be detached from or attached to the drum flanges.

So much of the structure as has been described is standard, each strip 21a representing a given channel or a given channel position. It will be recognized that if contacts 14 are to be cleaned in the usual manner, the selector 10 must be removed from the television receiver chassis, and then drum 11 must be detached to render said contacts accessible to a cleaning tool. My invention embodies the idea of placing a cleaning wiper or wipers on the drum so that, during normal channel selecting rotation of the drum, the wiper will relatively frequently wipe the contacts clean.

Normally, in any given location there are fewer available channels than there are strips 21a on the drum, so, usually, one or more of said strips are, in electrical effect, "dummies." I take advantage of this fact to replace one or more of the "dummies" with contact wipers. Thus, assuming that the original strip between the two central strips 21a in Fig. 1, is a dummy, that dummy strip is detached as has been described, leaving open the corresponding apertures 25 of flange 18, and leaving unoccupied the space between the corresponding lugs 26 on flange 19. Then my improved wiper and cleaner 30 is substituted in place of the detached dummy strip.

Wiper 30 is made up of a holder strip 21 of rigid material, fiber, for instance, having the same length as a

standard strip 21a, and having tongues 23 and 24 corresponding, respectively, to tongues 23a and 24a. However, the over-all width of strip 21 is preferably somewhat less than that of a standard strip 21a. While the strip 21 may be transversely arcuate to correspond to the curvature of a standard strip, it is so narrow and relatively thin that it is feasible to make it flat, as shown, in which event it is preferable that the undersides of tongues 23 and 24 be cut arcuately as at 23' and 24', respectively, to correspond with the curvature of a standard strip, and thus be taken by the flanges in a manner to prevent tilting or rocking of the wiper strip.

Preferably one edge of strip 21 is provided with an elongated notch 31, presenting oppositely facing shoulders 32 which are spaced apart by a distance slightly greater than the over-all length of the bank of contacts 14.

To strip 21 I apply a wiper pad 33 which may or may not be impregnated with a cleaning substance such as Vaseline. While I may use any suitable wiping material such as felt or fabric, I have found that nylon fabric or webbing particularly well serves the purpose, as it gives a gentle scouring action that performs the cleaning operation quickly and well, and yet does not unduly wear or abrade the contact surface.

As a preferred, but not limitative, means for applying and securing the pad to the holding strip, I make the pad in the form of a sleeve encircling the strip, the sleeve being entered in notch 31, whereby shoulders 32 hold it against longitudinal displacement. To insure that at least a portion of the sleeve is held outwardly far enough to effectively engage all the contacts 14 when the drum is properly rotated, I prefer to insert a narrow pad or strip 34, of somewhat resilient material, between the sleeve and strip 21 along the edge which corresponds to that edge of the standard strip 21a which lies adjacent to contact row 17. The narrow filler pad 34 may be made, for instance, of felt and may be cemented to the top of strip 21 before sleeve 33 is applied. Conveniently, the sleeve may be formed and secured in position by wrapping the nylon webbing fairly tightly around strip 21 and pad 34 and then "welding" the meeting edges of the webbing by the use of a solvent, such a junction being indicated at 35.

With the strip 21 and sleeve 33 assembled as described, it will be seen that it takes but an instant to retract spring hook 27, to insert the wiper 30 in the place of the removed "dummy" strip, and, finally, to release hook 27. Thereafter the wiper is releasably but firmly held to drum 11, and whenever the drum is rotated to carry the wiper past contacts 14, the latter will be wiped clean by pad 33. If the selector "position" occupied by wiper 30 becomes "active," it is but a moment's task to shift the wiper to

an "inactive" position and replace it with an "active" strip 21a.

Thus, in the normal practice of rotating drum 11 to select channels, there is an expectancy that contacts 14 will be relatively frequently wiped. The frequency periods between wipings may be reduced by providing a number of angularly spaced wipers on the drum, provided, of course, there are available appropriate "dummy" strips.

While I have shown and described a preferred embodiment of my invention, various changes in design, structure and arrangement may be made without departing from the spirit and scope of the appended claims.

I claim:

1. In combination, a channel selector drum embodying axially spaced flanges, a plurality of detachable contact strips extending axially of the drum from flange to flange and each forming an arcuate portion of the periphery of the drum, two of said strips being angularly spaced apart by reason of the absence of the normally intermediate strip, and a wiper replacing the absent strip, and embodying an elongated, substantially flat and rigid plate extending axially of the drum from flange to flange and detachably end-connected to said flanges, and a wiper pad applied to the outer face of said plate and extending longitudinally thereof, the outer face of the plate being substantially flush with the outer faces of the adjacent strips.
2. A terminal wiper embodying an elongated, substantially flat and rigid plate, a central tongue extending from one end of the plate and whose under face is cut arcuately, a pair of spaced tongues extending from the other end of the plate, the under faces of the tongues being cut arcuately with the same curvature as that of the central tongue, and a wiper pad applied to the upper face of the plate and longitudinally stopping short of said tongues.
3. A terminal wiper embodying an elongated, substantially flat and rigid plate, a central tongue extending from one end of the plate and whose under face is cut arcuately, a pair of spaced tongues extending from the other end of the plate, the under faces of the tongues being cut arcuately with the same curvature as that of the central tongue, there being a notch cut in one side edge of the plate, and a sleeve of wiping material extending longitudinally of and around the plate and through the notch.
